WALL SUPPORTED FOLDING DESK

Clyde S. Tompkins, Jr., Kansas City, Mo.

Application October 18, 1954, Serial No. 32,698

Term of patent 7 years

(Cl. D33—3)

Fig. 1.

Fig. 2.

Fig. 3.

To all whom it may concern:

Be it known that I, Clyde S. Tompkins, Jr., a citizen of the United States, residing at Kansas City, in the county of Jackson and State of Missouri, have invented a new, original, and ornamental Design for a Wall Supported Folding Desk, of which the following is a specification, reference being had to the accompanying drawing, forming a part thereof.

Fig. 1 is a front perspective view of the wall supported folding desk in the open position;

Fig. 2 is a front perspective view thereof in the closed position; and

Fig. 3 is a rear perspective view of the wall supported folding desk in the position illustrated in Fig. 2.

I claim:

The ornamental design for a wall supported folding desk, as shown.
